DESIGN FOR A BOTTLE OR SIMILAR ARTICLE

Augustus M. Clark, Millville, N. J., assignor to Whitall Tatum Company, Millville, N. J., a corporation of New Jersey

Application October 30, 1933, Serial No. 49,608

Term of patent 14 years

To all whom it may concern:

Be it known that I, AUGUSTUS M. CLARK, a citizen of the United States, residing at Millville, New Jersey, have invented a new, original, and ornamental Design for a Bottle or Similar Article, of which the following is a specification, reference being had to the accompanying drawing, forming part thereof.

In the drawing

Figures 1 and 2 are elevational views of a bottle, said views being taken substantially at right angles to each other.

I claim:

The ornamental design for a bottle or similar article substantially as shown.

In testimony whereof I have hereunto set my hand.

AUGUSTUS M. CLARK.
